UNITED STATES PATENT OFFICE.

WILLIAM McCLAVE, OF SCRANTON, PENNSYLVANIA, ASSIGNOR TO McCLAVE-BROOKS COMPANY, A CORPORATION OF PENNSYLVANIA.

FURNACE.

No. 849,912.

Specification of Letters Patent.

Patented April 9, 1907.

Application filed March 16, 1905. Serial No. 250,469.

To all whom it may concern:

Be it known that I, WILLIAM McCLAVE, a citizen of the United States, residing at Scranton, in the county of Lackawanna and State of Pennsylvania, have invented certain new and useful Improvements in Furnaces; and I do hereby declare the following to be a full, clear, and exact description of the invention, such as will enable others skilled in the art to which it appertains to make and use the same.

This invention relates to improvements in furnaces, and has particular relation to the structure of the furnace by which air in a heated condition may be delivered to the products of combustion as they pass from the fire-box and through the flame and smoke-flues of the furnace mechanism.

The invention comprises certain novel constructions, combinations, and arrangements of parts, as will be hereinafter fully described and claimed.

In the accompanying drawings, Figure 1 is a vertical central longitudinal section through a steam-boiler furnace constructed in accordance with the present invention, the boiler being shown in elevation. Fig. 2 is a view, partially in top plan and partially in horizontal section, showing the air-conducting flues and chambers. Fig. 3 is a detail perspective view of a bridge-wall-aperture-forming block or brick.

In consuming various kinds of fuel-coal in furnaces it is well known that large quantities of carbon are liberated, which escape before they can be caught by a sufficient quantity of oxygen to produce combustion, and the escape of these particles of carbon forms the dense black smoke which is so objectionable.

The present invention is designed for introducing and properly heating air and delivering it at such a point in the furnace with respect to the products of combustion that the escape of these liberated particles of carbon will be to a large degree prevented.

I am aware that heated air has been delivered into the combustion-chambers of furnaces or into the ash-pits thereof; but the structure to be described and claimed in this application is such as to enable me to utilize heat units which have heretofore been lost and also so deliver the air thus heated into the column of flame which passes from the

fire-box into the flue of a boiler-furnace that 55 advantageous results may be obtained in advance of that which has already been accomplished in this line.

I have illustrated in the accompanying drawings the manner in which I prefer to 6c construct furnaces for carrying the principle of the invention into effect and will now describe my improvements, reference to be had to the said drawings.

I have found in practice that the best results are obtained by constructing the furnace in such a manner that air may be delivered in a heated condition and either under a natural or forced draft into the stream column of flame and burning products of a furnace as they pass out of the fire-box and over the bridge-wall into the flame-flue instead of delivering the air directly into the fire-box or into the ash-pit.

Although the invention is applicable to 75 any style of boiler-furnace, I will describe the present invention with respect to a return-flue boiler of the usual type, such a boiler being indicated at 1 in the drawings and being mounted in suitable side or end walls in the 80 usual manner. The fire-box 2, however, is carried well forward of the end of the boiler, so that a large portion of the arched cover or roofing of the fire-box extends in front of the front end of the boiler, and the grate 3 occupies a similar position.

The present invention involves the peculiar construction of the furnace, whereby air may be delivered through the arched top of the fire-box, as well as through the specially-90 constructed bridge-wall at the rear end of the fire-box.

As seen best in Fig. 1, the greater portion of the fire-box 2, which projects beyond the end of the boiler 1, is formed with a cover or 95 top portion made up of two arches—an inner arch 4 and an upper or outer arch 5. A space 6 is left between these arches, which extends over almost the entire space between the two arches. The front portion of the arch 100 5 is formed with any suitable apertures 7, which extend through the material of the arch and communicate with the space 6 at the forward edge thereof, so that air may be admitted to said space at that point and be permitted to pass rearwardly through the space 105 and to discharge into the space below the boiler at the rear edge of the arches 4 and 5.

The space between the arches 4 and 5, at the rear edges thereof, is partially closed by a series of blocks or bricks 8, arranged to have suitable spaces 9 therebetween.

- 5 The structure by which the air delivered through the bridge-wall is properly heated also forms an important feature of the present invention. The bridge-wall 11 is extended rearwardly in the furnace from the fire-box 10 to a considerable extent, making the said bridge-wall comparatively thick, and interiorly of the bridge-wall is formed an air-chamber 12. The upper surface of the bridge-wall is inclined rearwardly and upwardly, so 15 that the rear upper edge of the bridge-wall approximates the lower surface of the boiler 1 more than any other portion of said bridge-wall. The volume of flame and burning gases and other products pass from the fire-box 2 upwardly over the inclined surface of the bridge-wall and against the under surface of the boiler, when it is more or less deflected and passes over the rear edge of the bridge-wall and downwardly into the flame-chamber 13. The volume of flame in this chamber strikes the flame-bed 14, which forms the floor of said chamber, and then rises again at the rear end of the said chamber 13, so as to pass through the flues in the boiler. The 20 flame-bed 14 is thus in a position to become highly heated under the action of the flames and burning products, and in order to intercept the heat units and make use of them as they tend to pass downwardly through the flame-bed 14 form a number of air-passages 15, which extend longitudinally through the lower portion of the said flame-bed. These 25 passages are preferably formed by arranging parallel vertical walls or partitions 16 in the said flame-bed, setting them a sufficient distance apart to make the passages 15 of a proper width to accommodate an ample flow of air beneath the flame-bed. The walls 16, in addition to forming the passages 15, act 30 as conductors for the heat received from the upper portion of the flame-bed 14 and carry it well downwardly upon each side of each column of air which passes through the passages 15. The columns of air thus become 35 thoroughly heated. The passages 15 extend to the rear face of the bridge-wall 11 and communicate with the chamber 12, formed therein, through a series of small passages 17. These 40 passages 17 are usually made of the same width as the passages 15, but are of much less depth and are preferably arranged in alignment with the upper edges of passages 15, as clearly shown in Fig. 1 of the drawings.
- 45 60 The rear ends of the passages 15 communicate with a transversely-arranged air-distributing chamber 18, which is mounted in the rear portion of the furnace-brickwork, and air is supplied to this chamber through an inlet-pipe 19, which extends rearwardly therefrom

and projects beyond the rear face of the rear furnace-wall. The rear ends of passages 15 are reduced in size by partially filling the same with brickwork, as at 16^a. This filling is arranged at the bottom of the passages 15, so as to leave air-inlet openings 16^b at the upper ends of the passages 15. Air will thus pass from the chamber 18 through the passages 16^b into the passages 15. The forming of the passages 15 of the depth described and shown is advantageous for two reasons—namely, first, that it makes it possible to bring a large quantity of air in contact with a considerable amount of heated surface, and, second, the passages 15 are deep enough to accommodate any collection of dust or foreign material which may be forced in with the air without any danger of clogging or closing the passages. The pipe 19 preferably enters the wall at a point above the chamber 18 and is bent downwardly, so as to enter the said air-chamber 18 from the top, as shown in Figs. 1 and 2. A natural draft may be permitted to carry air through said pipe into the chamber 18 and thence through the passages 15 to the bridge-wall; but I usually prefer to employ a fan, steam, or other blower for forcing air through said pipe and the passages above described. One end of the air-chamber 18 is capable of being opened and is normally closed by means of a door 20. Any accumulation of dirt or dust within the chamber 18 may be removed by opening said door. A cleaning-floor is also provided for the air-chamber 12 in the bridge-wall 11, the said door being indicated at 21.

The chamber 12 is formed with a series of outlet-passages 22, which lead therefrom in an inclined direction through the upper portion of the bridge-wall and deliver the air in its heated condition into the stream or column of flame and burning products which pass over the upper edge of the bridge-wall. The outlets of the passages 22 are preferably located a short distance below the upper rear edge of the bridge-wall 11, as clearly indicated in Fig. 1. These outlets may have downwardly-beveled surfaces at 23 for preventing the lodging of dirt, soot, or products of combustion which may be carried through the flame-flue and over the bridge-wall. Although the brick portion of the upper portion of the bridge-wall may be made by various kinds of brick or other similar material, I find it preferable to form special bricks for facilitating the construction of the air-passages 22.

In Fig. 3 I have illustrated a preferable form of brick for supporting the upper portion or edge of the bridge-wall 11. These bricks are constructed with a triangular body portion 55. The upper inclined edge of the body portion is formed with a series of stepped edges or shoulders, as at 56, the stepped portions being the height of a brick, 125 130

so that the front bricks of the wall 11 can be fitted upon the same, as shown in Fig. 1. The stepped portions 56 are only arranged upon each side of the upper inclined edge of said special brick, so that a groove or inclined channel 57 extends between the said stepped portions. The under edges of the opposite bricks are beveled, as at 58, to contribute to the formation of a smooth channel 10 above each of the special bricks just described. The special bricks are arranged side by side, so as to extend across the rear edge of the bridge-wall 11, and a passage 22 is thus arranged above each of said special 15 bricks. Of course I do not wish to be understood as confining myself to the use of said special bricks, for ordinary bricks properly cut and shaped may be employed within the spirit of the invention; but the bridge-wall 20 structure is greatly strengthened by the use of the special brick described. It will be evident that by this construction air may be taken in at the rear of the furnace and passed through the passages 15, which are formed in 25 the base or flame-bed, the said air thus being allowed to intercept a large portion of the heat units which would otherwise merely pass through the flame-bed, after which the air is delivered into the bridge-wall and in 30 passing upwardly through the same becomes further heated, so that it is delivered into the flames and burning products within the furnace in a highly-heated condition, and thus in readiness to combine with the liberated 35 particles of carbon which have not been consumed through the action of the oxygen present in the fire-box. The direction of the passages 22 is such that the streams of heated air forced through the bridge-wall will strike 40 the volume of flame which passes over the bridge-wall almost at right angles thereto, and although the said streams of air will then be considerably deflected they will be thoroughly infused and mingled in the mass of 45 flame and burning products which pass over the bridge-wall.

Any ordinary type of controlling mechanism may be provided for governing the admission of air through the aperture 7, and I 50 have illustrated a plate 32, mounted upon the arched cover or top of the fire-box and formed with a series of apertures spaced to coincide with and fit upon the aperture 7. Slidably mounted upon the plate 32 is a 55 slide 33, which is also provided with apertures corresponding to those of plate 32, the said slide being adapted to be moved for having its apertures coincide with the apertures of plate 32. If it is desired to cut off a portion of the flow of air, it is only necessary to move the slide 33 longitudinally to a greater or less extent for reducing the size of the inlet-openings. Any suitable means may be employed for controlling the action of the 60 slide 33, and I have illustrated in the draw-

ings a simple and preferable mechanism for this purpose comprising a rock-shaft 34, mounted in a bracket 35 and provided at its rear end with a crank-arm 36, which is connected by the link 37 with slide 33. The outer or front end of the shaft 34 is also provided with a crank-arm 38, which overhangs the front of the furnace. A depending rod, as at 39, may be secured to the free end of the crank-arm 38, and the operator of the furnace can easily grasp and pull down or push up said rod 39 for changing the position of the slide 33.

While it is evident that a natural draft may be employed at the rear of the furnace 80 for supplying air to the bridge-walls and passages in the flame-bed, it is preferable to use a forcing means at this point. When, however, a natural draft is sufficient, it is only necessary to leave the rear end of the pipe 19 85 open, and the natural suction produced by the movement of the flames and products of combustion beneath the boiler will of course draw the air through the said passages and bridge-wall.

For supplying forced draft to the bridge-wall I preferably employ a steam-jet 40, which is located opposite the open end of the pipe 19 and connected with piping 41, which communicates with any suitable source of 95 steam-supply. When a blower of this kind is employed, it is preferably supplied with superheated steam from a coil of pipe 43, disposed intermediate the length of the pipe 41 and arranged in a recess 42, formed in the rear wall of the furnace adjacent to the fire-brick lining 44. A valve 45 is preferably located in pipe 41 adjacent to the blower for controlling the passage of steam thereto. The valve is preferably provided with an operating-lever 50, which is pivoted adjacent to the valve and is normally maintained in a lowered inoperative position by a weight 51. A chain 52 is connected with the lever 50 and is passed over the furnace to the front, suitable pulleys being provided for supporting the chain for obviating friction. A suitable adjustable screw 53 is arranged at the front of the furnace and engages the front end of the chain 52 in such manner that the setting 105 of the screw will operate to lift the lever 50 or permit the same to drop, according to the direction of the operation of the screw.

An aperture or apertures 49 may be formed in the arch 5 for permitting access to the 110 space 6 for facilitating the removal of foreign substances.

Having now described my invention, what I claim as new, and desire to secure by Letters Patent, is—

1. A furnace structure, comprising inclosing walls arranged to form a fire-box and a flame-chamber, a hollow bridge-wall arranged between the fire-box and the flame-chamber, means being provided for affording 115

communication between the interior of the bridge-wall and the flame-chamber, air heating and conducting passages being formed in the floor of the flame-chamber, each of said 5 passages being reduced in size at its ends and enlarged at its intermediate portion, each of the said passages communicating with the interior of the bridge-wall at one end, and means for delivering air to the other end of 10 each of said passages.

2. A furnace structure, comprising inclosing walls arranged to form a fire-box and a flame-chamber, a hollow bridge-wall disposed between said fire-box and flame-chamber, the bridge-wall being formed with 15 means of communication between its interior and the furnace-inclosure, air heating and conducting passages communicating with the interior of the bridge-wall, each of 20 said passages being formed small at each end and enlarged intermediate its length, a distributing-chamber disposed transversely of the flame-chamber and communicating with the ends of the air heating and conducting 25 passages farthest distant from the bridge-wall, and means for supplying air to said distributing-chamber.

3. In an air-feeding mechanism for furnaces, the combination with a furnace-inclosure, of a hollow bridge-wall arranged 30 therein and dividing the same into a fire-box and a flame-chamber, a flame-bed arranged in said chamber and formed with a plurality of longitudinally-arranged parallel passages, 35 a transversely-arranged air-chamber communicating with said passages, each of the passages being relatively small at the point of communication with the air-chamber and relatively large beyond the air-chamber, 40 means for supplying air under pressure to the air-chamber, means of communication between said passages and the interior of said bridge-wall, and means for delivering air from the bridge-wall to the furnace-inclosure. 45

4. In an air-feeding mechanism for fur-

naces, the combination with a furnace-inclosure, a hollow bridge-wall arranged therein, of air-heating passages formed in the floor of the furnace-inclosure and communicating with the interior of the bridge-wall, 50 a supply-chamber arranged transversely of and communicating with the ends of said passages farthest from the bridge-wall, the bridge-wall being provided with means of communication between the interior of the bridge-wall and the furnace-inclosure, and an air-supply pipe extending from outside the furnace-inclosure into the same above the transversely-disposed chamber and bent 55 downwardly and extending into said chamber through the top.

5. A furnace structure, comprising inclosing walls, a bridge-wall formed therein having angular bricks arranged at the upper edge thereof and formed with grooves or 60 passages, the said angular bricks also supporting adjacent bricks in such a manner as to complete the air-passages along said grooves, and means for delivering heated air through the said grooves into the flame-chamber of 70 the furnace.

6. A furnace structure, comprising inclosing walls and a bridge-wall formed therein, said bridge-wall being made hollow, approximately triangular bricks or blocks arranged across the upper edge of the bridge-wall each of said blocks having a plurality of stepped shouldered portions leaving a space between them and top bricks fitting upon said shouldered portions and completing 80 passages in connection with the spaces of the triangular blocks or bricks and means for delivering air in a heated condition through the said passages.

In testimony whereof I affix my signature 85 in presence of two witnesses.

WILLIAM McCRAVE.
